UNITED STATES PATENT OFFICE.

RAYMOND A. HEISING, OF EAST ORANGE, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

Application filed June 5, 1920. Serial No. 386,743.

To all whom it may concern:

Be it known that I, RAYMOND A. HEISING, a citizen of the United States, residing at East Orange, in the county of Essex, State 5 of New Jersey, have invented certain new and useful Improvements in Signaling Systems, of which the following is a full, clear, concise, and exact description.

This invention relates to oscillation generating systems and is exemplified herein in a modulating system of the type wherein the unmodulated component of the modulated carrier frequency current is wholly or partly suppressed. The invention comprises, certain 10 combinations and methods useful in signaling and equivalent systems which are hereinafter described.

An object of the invention is to provide a generator of modulated oscillations wherein 20 the side frequencies, which for some purposes constitute the useful components of a modulated carrier current, may be conveniently separated and utilized and wherein the unmodulated component of carrier frequency may be wholly or partly suppressed. For this purpose means are provided including a branch path of zero reactance and impedance for current of the carrier frequency and of substantial impedance for the components of current corresponding to the side 25 frequencies, which components are therefore caused to flow in another branch path wherein the energy may be utilized or wherefrom it may be drawn for utilization. The circuit 30 of zero resistance and reactance comprises, in a preferred form, another oscillator having a frequency equal to the carrier frequency of the oscillator whose oscillations are modulated. The branch path of zero reactance for the carrier frequency is designed 35 to have a proportionally great self-inductance and small capacity whereby the unbalanced reactance for the side frequencies is caused to be proportionally great.

From one aspect the invention comprises a plurality of oscillation generators, each connected to a circuit to balanced points of which a load circuit is connected. When the oscillations of part of the oscillators are modulated, the load circuit terminals are unbalanced with respect to the side frequencies to a greater extent than with respect to the carrier frequency. Discrimination is thereby produced whereby the component of carrier 55 frequency may be wholly or partly sep-

arated. Ordinarily it will be sufficient to provide two oscillators and cause modulation of the oscillations of one thereof as hereinafter described.

An important feature of the invention resides in the employment of a plurality of thermionic or equivalent oscillators each having a tuned circuit in series with and constituting a load circuit for the other. As herein described, each oscillator constitutes 60 a zero resistance load circuit. Another important feature resides in the use of a zero resistance circuit for separating the components of a complex current.

The invention also comprehends certain 70 features of a receiving system which may be combined in a transmitting system for duplex signaling so that certain elements perform useful functions both in transmitting and in receiving, or may be used independently.

The invention will be described in detail in connection with the accompanying drawings wherein Fig. 1 is a circuit diagram 80 representing a modulating system in accordance with the invention: Fig. 2 is a radio transmitting system including the invention: and Fig. 3 comprises in one circuit a transmitting and receiving system for duplex 85 operation.

In Fig. 1 are shown two oscillating systems, A and B. Each system comprises a thermionic device 1, of the type including an electrically heated filamentary cathode, an anode, and a discharge controlling element in the form of a grid, located, in the present instance, between the anode and the cathode. A highly evacuated envelope encloses these elements. The electrodes and grids are respectively connected, in a manner 90 well-known in the art, to tuned circuits, each consisting of capacities 2, inductances 3 and capacities 4. These tuned circuits instead of being closed individually, each upon itself, are closed by connecting them both in 100 a series circuit 5. Around the tuned circuit of the system B is shunted a tuned circuit 6, including capacity 7 and inductance 8. A suitable output line or load circuit 10 is coupled to the circuit 6, in any suitable manner, as by including coil 11 therein and electromagnetically coupling the coil 11 to the coil 8. Means are provided for causing the system A to generate modulated oscillations. 105 This may be accomplished by producing low 110

frequency variations in a suitable circuit, as for example, the microphone circuit 12 and impressing them upon the grid circuit 13 of the system A.

5 *Operation.*—Let it be assumed that each system A and B of Fig. 1 is generating oscillations of a suitable carrier frequency, the frequency being the same for both systems. Then the tuned circuit 2, 3, 4 of system B will furnish a path of negligible reactance for the oscillations generated by system A. Furthermore, since the system B is also an oscillator the path 2, 3, 4 will be of negligible or zero resistance for the 10 carrier oscillations generated by system A. Since the circuit 6 is in effect connected directly across points *a*, *b* of the circuit 5, across which no difference of potential exists, because the generators are adjusted to normally generate equal voltages, little current 15 will flow in the circuit 6. Let the path 2, 3, 4 be a stiff resonant circuit and the circuit 6 a loose resonant circuit, that is, although the circuits are tuned to the same 20 frequency, the circuit 6 will have relatively small inductance and large capacity while the path 2, 3, 4 will have relatively large inductance and small capacity. When speech or equivalent low frequency variations are 25 produced in the microphone circuit 12, the oscillations of the system A will be modulated. As is known in the art, if oscillations of carrier frequency *p*, be modulated in accordance with lower frequency signaling 30 variations *s*, there will, in general, be produced a composite current comprising the frequencies *p*, *p*—*s* and *p*+*s*, of which the two latter are known as the side frequencies and the former as the unmodulated component. Since the path 2, 3, 4 is of zero 35 resistance and reactance for the unmodulated component but has a relatively large unbalanced reactance for frequencies slightly differing therefrom, the side frequencies 40 will be shunted to a large extent through circuit 6 and impressed upon the work circuit 10. However, only a small proportion of the unmodulated component will pass through the circuit 6, this proportion depending in general, upon the effective resistance of this circuit.

In Fig. 2, the system A is caused to generate modulated oscillations in a different manner than in Fig. 1, namely by varying the plate potential across the tube 1 in accordance with signaling frequency variations in a microphone circuit 12. In this system, commonly known as the "constant current modulation system," the microphone circuit 12 acts to vary the impedance of a vacuum tube 14, these elements together constituting a variable impedance system C. The variable impedance system is connected in shunt to the system A with respect to the source of current 15 and the signaling choke

coil 16. Since published descriptions of this type of modulating system exist, more detailed description will be unnecessary. In general, however, the system A may comprise any source of modulated carrier frequency oscillations. The system B likewise comprises an oscillation generating system of a known type wherein a vacuum tube 1, supplied with space current from source 17 through a choke coil 18, produces oscillations in the circuit comprising the capacity 4, inductance coil 3 and capacity 2. For radio transmission a suitable antenna is connected across the points *a*, *b* which correspond to the points *a*, *b* of Fig. 1. With both systems A and B operating, but during an instant when no signals are being transmitted, oscillations will be produced in the closed circuit comprising the sets of elements 2, 3, and 4. Corresponding to Fig. 1, the path 2, 3, 4, of the system B is a stiffly resonant tuned circuit of zero impedance to the carrier frequency. When the oscillations of the system A are modulated, points *a*, *b* will become unbalanced with respect to the side frequencies thereby causing the energy of the side frequencies to be transferred to the circuit 6 and radiated.

The duplex radio station shown in Fig. 3, comprises transmitting means similar to the arrangement of Fig. 2. There is provided, however, additional means for receiving, consisting of the tube 19, whose grid is connected in parallel with the source 15 and the choke 16. A condenser 20 keeps direct current from the source 15 out of the grid circuit of the tube 19. Between the grid and the filament of the tube 19 is connected a highly resistive leak path 21. Suppose now, that side frequencies, either with or without an unmodulated component, are being received by the antenna 6. Since the tuned circuit 2, 3, 4 of system A is a stiffly resonant circuit while the circuit 2, 3, 4, of system B is a loose resonant circuit, a proportionally greater part of the received energy will pass into the system A. If, however, the tuned circuits of the systems A and B are identical, then approximately one-half of the received energy will pass into each system. In either case, however, the energy of the received side frequencies which passes into the system A will be impressed upon the grid circuit of the tube 1. Owing to the detecting action of the tube 1, beats will be produced between the carrier frequency produced by system A and the received side frequencies. If the oscillation frequency of the system A is, in the case of telephony, equal to the carrier frequency of the received signals, these beats will be in the form of speech frequency currents. In the case of telegraphy, however, where the frequency of the system A is properly adjusted, these beats will be of a suitable audible frequency.

The energy of the beat component in the output circuit of tube 1, will be impressed upon the grid circuit of the amplifying tube 19 and the resulting signal is received in 5 any suitable manner, as for example, by listening to a telephone receiver 22, connected to the output circuit of the tube 19. The circuit 6 is not necessarily an antenna or some form of load circuit, but may be a 10 transmission line or a filter circuit connected with an antenna or a transmission line and may include repeaters or other similar apparatus.

While certain complete systems embodying the features of the invention are described herein, the invention is not limited to any particular embodiment but all or part of the features thereof may be utilized in other systems. The novel features believed to be inherent in the invention are defined in the appended claims.

What is claimed is:

1. A modulating system comprising an oscillator, means for causing the oscillator 25 to generate modulated current, a plurality of paths for the passage of said current, one of said paths including a stiffly resonant circuit of zero reactance and resistance for the unmodulated component of the modulated current, and another of said paths including a loosely resonant circuit tuned to the same frequency.

2. A modulating system comprising a source of voltage having the wave form of 30 a modulated current having an unmodulated component, a pair of paths connected in parallel to said source, one of said paths comprising a stiffly resonant circuit of zero reactance and resistance for the unmodulated component of the modulated current, and the other of said paths including a loosely resonant circuit tuned to the same frequency.

3. A modulating system comprising a source of voltage having the wave form of 45 a modulated current including an unmodulated component, a plurality of paths resonant to the same frequency connected in parallel with respect to said source, said paths being of different impedance to the side frequencies of the modulated current.

4. A high frequency circuit in combination with a plurality of electron discharge oscillation generators having reactive paths included in series with respect to said high frequency circuit.

5. A circuit tuned to a given frequency in combination with a plurality of individually complete self-synchronizing oscillation generators having reactance elements in effective serial relation to said circuit.

6. In combination, a series circuit, and a plurality of oscillation generators arranged in series with and constituting parts of said circuit, each said generator comprising a 65 series path tuned to have substantially zero

reactance for current of a given frequency to be generated.

7. A system comprising a series circuit, a plurality of independently tuned portions in said circuit, said portions being resonant to 70 the same frequency, a plurality of thermionic devices, and an input circuit and an output circuit for each device, the input circuit and output circuit of each device being connected to one of said portions respectively.

8. A modulating system comprising a generator for producing oscillations of a given carrier frequency, means associated therewith to cause modulated oscillations to be 80 generated thereby, a path of zero reactance and resistance for current of the carrier frequency connected to said generator, and a branch path in shunt to said first mentioned path, said branch path being similarly tuned 85 but of looser resonance.

9. A modulating system comprising a pair of oscillation generators connected to generate oscillations in a closed circuit, a load circuit connected between two points in said 90 closed circuit, and means for causing variations in amplitude of the voltage produced by one of said oscillators.

10. A modulating system comprising two generators of alternating current included 95 in a closed circuit, a path connecting two normally balanced points on said circuit, and means for disturbing the balance by causing one generator to produce variable 100 oscillations.

11. In combination two electron discharge devices, each having an anode, a cathode and a discharge controlling element, and appropriate means including circuits having included therein a tuned path whereby each 105 functions as an oscillation generator, the tuned path of each generator being in a circuit through which the other tends to drive current.

12. A system comprising two sources of 110 high frequency oscillations, means for modulating the oscillations from one of said sources, means for radiating the modulated oscillations, said radiating means constituting a receiving means for impressing received oscillations upon said sources, one of said sources being selective of the received oscillations, said source functioning to combine the energy of received oscillations impressed thereon with the generated oscillations, and indicating means for indicating the signals resulting from said combination.

13. A system comprising two sources of oscillations, a source of signal waves, said 115 sources of oscillations cooperating to transmit waves varied in accordance with said signal waves, receiving means comprising one of said sources of oscillations, and indicating means to indicate the signals received 120 by said receiving means.

14. An electrical network comprising three branches terminating in a common pair of points, said branches being similarly tuned, at least one of said branches being of zero effective resistance for current of a certain frequency and one of said branches having a flatter resonance characteristic than another.
15. A circuit comprising a source of periodic electromotive force having a plurality of frequency components, a plurality of similarly tuned paths in parallel to each other with respect to said source, one of said paths being of zero effective resistance for one of said components but not for another thereof.
16. A receiving system comprising a signaling conductor circuit, a plurality of tuned paths connected in parallel to each other with respect to said circuit, said paths being similarly tuned but having different ratios of self-inductance and capacity.
17. A system for separating the modulated and unmodulated components of a modulated current which comprises a source of modulated current and a pair of paths tuned to the same frequency but having different effective values of self-inductance and capacity, said paths being connected in parallel to each other with respect to the source of modulated current.
18. The method of selectively receiving a modulated wave which comprises impress-
- ing the wave upon circuits connected in parallel to each other with respect to the source of said modulated wave, said circuits being resonant to the same frequency but of different impedance to certain frequency components of the modulated wave.
19. The method of selectively separating the components of a complex current which comprises passing the current through a plurally branched circuit, one branch of which has zero effective resistance.
20. A transmitting system comprising a source of high frequency oscillations and two parallel paths of constant effective resistance continually connected to said source and tuned to the same frequency, the ratio of self-inductance to capacity being different in the two paths, and means for transmitting signals while maintaining the state of continuity of said paths with respect to said source.
21. A radio system comprising a receiving antenna for receiving modulated carrier waves, means including a circuit for supplying and means for combining locally produced waves of the carrier frequency of the incoming waves with said incoming waves, and means for preventing the supplied locally produced waves from reaching the antenna and being radiated.

In witness whereof, I hereunto subscribe my name this 27th day of May, A. D. 1920.

RAYMOND A. HEISING.
